UNITED STATES PATENT OFFICE.

VALENTINE VON DER LIN AND SIMON JULIUS VON DER LIN, OF NEW YORK, N. Y.

FURNITURE-TREAD.

1,173,990.

Specification of Letters Patent. Patented Feb. 29, 1916.

Application filed May 1, 1915. Serial No. 25,287.

To all whom it may concern:

Be it known that we, VALENTINE VON DER LIN and SIMON J. VON DER LIN, citizens of the United States, and residents of the borough of Manhattan, city, county, and State of New York, have invented certain new and useful Improvements in Furniture-Treads, of which the following is a specification.

10 The main object of our present invention is to afford a very simple, cheap, yet effective adjustable tread for application to the legs or supports of tables or other articles of furniture, whereby variations in length 15 of support or inequalities of floor surface may be quickly and conveniently compensated for within prescribed limits. Heretofore, as in our Letters Patent No. 1,123,959, and No. 1,123,960, issued to us 20 January 5th, 1915, and in our concurrent application Serial No. 876,772, filed Dec. 12, 1914, we have shown and described three-part devices of this character which have proven practical and effective in use, although somewhat expensive to manufacture. 25 By our present two-part structure we are enabled to attain like results much more economically as related to cost of production without detracting from the utility or 30 convenience of the device.

Hence our invention consists in the specific construction and arrangement of parts herein described and claimed,—distinctive features being an internally threaded member 35 U-shaped in vertical section and hence closed at bottom to form a central tread or contact surface, said tread member screwing directly upon a screw post attached to the furniture support, and in the means provided 40 whereby these parts may be held in prescribed relation upon and with relation to each other while at the same time the extent of adjustment is limited and the parts coupled together, all as hereinafter 45 more fully set forth.

In the accompanying drawings, Figure 1, shows our adjustable tread in elevation; Fig. 2, is a central vertical sectional elevation of the same and the lower part of 50 the furniture support to which it is applied, as upon plane of line 2—2 Fig. 3; Fig. 3, is a view of the under side of the device; Fig. 4, a detail elevation of the screw post; Fig. 5, a detail elevation of the tread; Fig. 55 6, is a transverse section taken upon plane of line 6—6, Fig. 2.

Provision is made for attaching what may be designated as the base plate B, rigidly to the leg or support L, of a table or other article of furniture, by any suitable mechanical expedient. As shown in the drawings the base plate is annular and is formed with screw holes b , b , for ordinary wood screws b' , b' , although this is not a feature of the invention, the main function 65 of the base plate B, being the rigid support of the screw post B'. This post B', may be made hollow to save metal and weight, and its lower portion is formed with the peripheral thread b^2 , between which and the 70 under side of the base plate B, is the cylindrical shank b^3 , of less diameter than said threaded lower portion of the post,—the upper convolution of the thread b^2 , forming an annular shoulder b^4 . 75

The tread member T, consists of a hollow cup-shaped single piece which is U-shaped in central longitudinal section, as will be seen by reference particularly to Fig. 2, the closed bottom forming the bearing or tread 80 t , for contacting directly and centrally (axially as related to the length of the member T,) with the floor f , or other sustaining surface. The tread member or thimble T, thus shaped is formed with an 85 internal screw thread t' , for engagement with the male screw thread b^2 , on the lower end of the post B', and it will be noted that the construction in this respect is materially different from that disclosed in the Letters 90 Patent and application hereinbefore recited, in which the tread member is threaded externally for engagement with an adjusting sleeve or nut. In fact, to all intents and purposes, in the present case we 95 have combined the tread member and the sleeve or nut member in one piece and rotate the tread member directly on the post or stud member, thereby eliminating one member from the combination of parts 100 while attaining a like function in so far as the adjustability of the tread is concerned,—the decrease in cost of production attained by this simpler structure being an important factor in a commercial sense. 105

In order to couple the tread member T, to the post B', and provide means for clamping the tread member T, in a desired position upon the post B', we use one or more set screws t , laterally positioned in the neck or upper portion of the tread member T, and opposed to the contracted cylindrical por-

tion b^3 of the screw post B'. When these are screwed inward with their points projecting above the peripheral depth of the male screw b^2 , the upper convolution of which, acting as an annular shoulder b^4 , as before set forth, it is obvious that the two parts, the post B', and the tread member T, will be thereby coupled together,—the annular shoulder b^4 , limiting the extent of adjustment of the tread member downward, and the base plate B, limiting the extent of its adjustment upward. When the tread member T, is positioned to contact properly with the floor or other sustaining surface f , the set screw or screws t^2 , are tightened to impinge forcibly against the contracted cylindrical portion b^3 , of the screw post B', thereby locking the tread member T, in the ascertained and prescribed portion. It will thus be seen that the contracted cylindrical portion b^3 , of the screw post B', is an important factor in that it affords a margin of adjustability above and beyond the male screw thread b^2 ; so that the latter is left intact and is not damaged or marred as would be the case if the set screws t^2 , impinged directly thereon.

The tread member T, is preferably formed with a peripherally roughened zone t^3 for finger contact, to facilitate manipulation.

What we claim as our invention and desire to secure by Letters Patent is,

1. The furniture tread herein described, comprising a base plate, means for securing the same to a furniture leg or support, a post on said base plate formed with a screw threaded lower portion and a contracted cylindrical portion between said screw threaded portion and the base plate, an internally threaded one piece tread member U-shaped in longitudinal cross section engaging with said threaded post, the closed end of said tread member forming a central axial contact surface for the purpose set forth, and one or more set screws positioned laterally on the tread member and opposed to the reduced cylindrical portion of the said screw threaded post.

2. The furniture tread herein described comprising a base plate, means for attaching the same to a furniture leg or support, a screw threaded post on said base plate, an internally-threaded tread member U-shaped in longitudinal cross section engaging with said threaded post, the closed end of said tread member forming a central axial contact surface for the purpose set forth, and means for clamping the said tread member to said post.
